(57) **CLAIM**

The ornamental design for a power supply bezel, as shown and described.

DESCRIPTION

FIG. 1 is a front perspective view of the power supply bezel comprising the present invention;

FIG. 2 is a front view thereof;

FIG. 3 is a right side view thereof;

FIG. 4 is a left side view thereof;

FIG. 5 is a back view thereof;

FIG. 6 is a top view thereof;

FIG. 7 is a bottom view thereof;

FIG. 8 is another front perspective view of the power supply bezel comprising the present invention;

FIG. 9 is another front view thereof;

FIG. 10 is another right side view thereof;

FIG. 11 is another left side view thereof;

FIG. 12 is another back view thereof;

FIG. 13 is another top view thereof;

FIG. 14 is another bottom view thereof;

FIG. 15 is another front perspective view of the power supply bezel comprising the present invention;

FIG. 16 is another front view thereof;

FIG. 17 is another right side view thereof;

FIG. 18 is another left side view thereof;

FIG. 19 is another back view thereof; and

FIG. 20 is another top view thereof; and,

FIG. 21 is another bottom view thereof.

Broken lines are shown for illustrative purposes only and form no part of the claimed design.
